UNITED STATES PATENT OFFICE.

HANS ROSENTHAL, OF BERLIN, GERMANY, ASSIGNOR TO JULIUS PINTSCH AKTIEN-
GESELLSCHAFT, OF BERLIN, GERMANY.

RAILWAY-CARRIAGE LIGHTING.

1,235,383.

Specification of Letters Patent. Patented July 31, 1917.

Application filed July 15, 1913, Serial No. 779,179. Renewed March 9, 1917. Serial No. 153,741.

To all whom it may concern:

Be it known that I, HANS ROSENTHAL, a citizen of the German Empire, and residing at Berlin, German Empire, have invented certain new and useful Improvements in Railway-Carriage Lighting, of which the following is a description.

When it is desired to regulate the turning down of the lights of a whole carriage, not only by the attendant, altogether from the end of the car, without his having to attend to each lamp separately, but also to enable each passenger to adjust the light in his compartment as he wishes to "light" or "dark" with a single pipe connection for the gas or mixture of gas and air, considerable difficulties arise. If all the lamps are adjusted to full pressure, or "light" it is easily possible to throttle the gas pressure at the end of the carriage, so that all the lamps will be turned down. If, however, one or other of the passengers turns down his individual light, so that a second throttling of the pressure occurs in the lamp, it is possible that the light will go out entirely owing to too great a reduction of the pressure, and to the fact that the other lamps, the individual cocks of which still stand open or at full pressure, would receive all the gas.

The object of the present invention is, in such a case, to provide means by which, when some of the lamps are burning full and others turned down by the passengers, to enable the attendant even then to effect a general turning down of all the lights from the end of the carriage. This is effected by providing the gas feed with a low pressure, which, however, remains constant, even with varying gas consumption in the various gas lamps, by the aid of an auxiliary pressure regulator, attached to the gas holder and to the main gas regulator, and adapted to control the latter, or by a separate auxiliary regulator to control the pipe system. In the accompanying drawings Figure 1 is a diagrammatic representation showing the general arrangement of the gas holder, regulators, pipes, cocks and lamps. Figs. 2 and 3 are diagrammatic vertical sections showing two modifications of the embodiment of the main and auxiliary regulators. Fig. 2^a is a detail.

In the general arrangement of the plant illustrated in Fig. 1, the gas passes from

the holder or recipient *a* through a pressure regulator *b*, adjusted to the ordinary working pressure; it then passes the cock *c*, and pipe *o* and is fed to the lamps through the pipe *f*. A second regulator *d*, adjusted to a less pressure is mounted in a branch pipe *o'* and is provided with a cock *e*. Beyond the cocks *e* and *c* the two conduits are combined to form a common conduit *f* through which the gas or mixture of gas and air is conducted to the various lamps *g'*, *g²*, *g³*, *g⁴* by means of branch pipes *f'*, *f²*, *f³*, *f⁴*.

Each of these lamps possesses one "light" and "dark" adjustment mechanism for the passengers, illustrated, for instance, in connection with the lamp *g'* and consisting, for instance, of a gas cock *h* having a change lever *i* and a by-pass *k* with a throttling mechanism *l*. This mechanism is known and forms no part of the present invention.

Assuming that the attendant has opened the system for the use of the passengers the cocks *c* and *e* will be in the position shown in the drawings, *i. e.* gas will only pass through *c* to the pipe *f* under normal pressure, *e* being closed. In this case the passengers can adjust their lamps to "light" or "dark" by operating the lever *i* as they desire.

If, on the other hand, the railway attendant has closed the cock *c* and opened *e*, there will be so little pressure in the pipe *f* and consequently in the lamp, that the flame will still burn "dark" even if the "light" and "dark" adjusting device is adjusted to "light," unless special adjustment of the reduced pressure in *d* is made in relation to the normal pressure in *b*.

If however the reduction of pressure in *d* is adjusted in relation to the normal pressure in *b* and the throttling in the by-pass pipes *k* correspondingly regulated, it is possible to supply the turned down flame with sufficient gas, even when some of the "light" and "dark" adjusting devices are in the reduced position and some fully open. Since, however, the adjustment of the lamp to the full light when all the lamps are turned down, may be considered an exception, the increase in gas consumption of about 50-100% would not have sufficient influence to prevent the small flames from continuing to burn.

The reduced pressure in the pipe *f* may

also be attained, by means of the arrangements shown in Figs. 2 or 3.

In Fig. 2 the object is attained by the arrangement of a pressure chamber *d* having a membrane *m* located above the pressure regulator *b* and having a special form of gas cut off *e'*, which relieves the pressure chamber *d* by being placed into communication with the outer air when the system is working at normal working pressure. In this case the gas passes from the holder *a* to the pressure regulator *b* the cock *e* and the conduit *f* to the lamps. When the latter are burning at normal pressure the cock *e'* is adjusted to the position shown at Fig. 2^a, *i.e.* the interior of the regulator *d* is in communication with the open air through ports *e²*, *e³*. The pressure chamber *d* has a membrane *n* connected rigidly to the membrane *m* of the regulator *b*. When the cock *e'* is turned to the position shown in Fig. 2 and the branch pipe *o'* thus opens up communication between the interior of the regulator *d* and the pipe *f*, full gas pressure will dis-

75 tend the membrane *m* downwardly and exercise pressure on the membrane *n* of the regulator *b* thus throttling the gas supply to *f* and causing all the lamps to burn small.

The device illustrated in Fig. 3 is the same as the other devices, from the pipe *f* onward. In this case, the idea of the invention is carried out by means of a special construction of the pressure regulator *b* according to which, in addition to the normal membrane *n*, a second membrane *m'* is fitted in the bottom of the regulator *b*. The branch pipe *o'* opens into the main regulator *b* beneath the membrane *m'*, which latter is connected by a lever system *s'* *s²* fulcrumed at *s*, with the main membrane *n*, said lever system carrying the regulating valve *r*. The gas passes through pipe *o* to the main pipe *f* to supply normal pressure to the lamps when the cock *t* is closed. The construction of cock *t* is similar to that of cock *e'*. Thus when the cock *t* is closed the space beneath the membrane *m'* is in communication with the open air and normal pressure passes to the supply pipe *f*. If the cock *t* is opened, full pressure passes be-

neath the membrane *m'* and increases the load on *r*, thus decreasing the pressure.

I claim as my invention:

1. In a plant for lighting railway carriages the combination with the ordinary pressure regulator and full pressure pipe system, of an auxiliary regulator associated therewith, means for placing said auxiliary regulator in communication with the full pressure pipe system and means for cutting off the ordinary pressure regulator from the system.

2. In a plant for lighting railway carriages with gas comprising a gas holder and a single pipe conduit to connect up the lamps, a cut off valve in the said conduit, an ordinary pressure regulator in the main pipe between the cut off and the gas holder and a controlling regulator connected up to the ordinary pressure regulator, means for placing said controlling regulator in communication with the ordinary regulator to reduce the gas pressure in the pipes and means for opening the controlling regulator to the air to relieve the said ordinary regulator.

75 3. In a plant for lighting railway carriages, of the class specified, the combination with the ordinary regulator of an auxiliary regulator connected up to the ordinary regulator and means for placing said auxiliary regulator in communication with the full pressure pipe system as also means for cutting off such communication and placing the said auxiliary regulator in communication with the open air for the purpose specified.

4. In a plant for lighting railway carriages comprising in combination a full pressure pipe system, including a main gas holder, an ordinary pressure regulator and an auxiliary regulator attached to said gas holder and to said ordinary pressure regulator and adapted to control the latter.

In testimony whereof I affix my signature in the presence of two witnesses.

HANS ROSENTHAL.
